(57) **CLAIM**

I claim the ornamental design for a breastfeeding simulation device, as shown and described.

DESCRIPTION

FIG. 1 is a perspective view of a breastfeeding simulation device showing my new design;

FIG. 2 is a top view thereof;

FIG. 3 is a right-side view thereof;

FIG. 4 is a left-side view thereof;

FIG. 5 is a front view thereof; and,

FIG. 6 is a bottom view thereof.

The broken lines in the drawings represent unclaimed environmental subject matter.
